DESIGN.

S. CRIMI.

COMBINED CLOCK AND PHONOGRAPH CABINET.

APPLICATION FILED FEB. 23, 1921.

57,892.

Patented May 17, 1921.

Inventor:

Salvalore Crimi,
By his Attorney, Leo. Willard

UNITED STATES PATENT OFFICE.

SALVATORE CRIMI, OF NEW YORK, N. Y.

DESIGN FOR A COMBINED CLOCK AND PHONOGRAPH CABINET.

57,892.

Specification for Design.

Patented May 17, 1921.

Application filed February 23, 1921. Serial No. 447,327. Term of patent 7 years.

To all whom it may concern:

Be it known that I, SALVATORE CRIMI, a subject of the King of Italy, having declared my intention of becoming a citizen of the United States, residing at the borough of Manhattan, city, county, and State of New York, have invented a new, original, and ornamental Design for Combined Clock and Phonograph Cabinets, of which the following is a specification, reference being had to the accompanying drawing, forming part thereof.

The figure is a perspective view of a combined clock and phonograph cabinet, showing my new design.

I claim:

The ornamental design for a combined clock and phonograph cabinet, as shown.

SALVATORE CRIMI.
